UNITED STATES PATENT OFFICE

ARTHUR W. WARNER, OF MEDIA, AND ROSCOE F. BALLARD, OF CHESTER, PENNSYLVANIA, ASSIGNORS TO TUNNEL AND MINE MACHINERY COMPANY, OF PHILADELPHIA, PENNSYLVANIA, A CORPORATION OF NEW JERSEY

JACK MECHANISM

Original application filed June 16, 1930, Serial No. 468,338. Divided and this application filed April 11, 1931. Serial No. 529,516.

This invention relates to jack mechanisms and a jack for use therein, and more particularly to a jack especially adapted for use in conjunction with tunnel-forming apparatus such as illustrated in our prior application, Serial No. 468,338, filed July 16, 1930, for method of and apparatus for forming tunnels, of which application this application is a division.

10 An important object of the invention is to provide jacking apparatus comprising a plurality of jacks and means whereby the jacks may be subdivided in series which are alternately operated so that one series may be employed in elevating or applying stress to a structure while a second series is withdrawn to permit insertion of elements through which further stress is to be applied, the alternate use of the series in this manner permitting substantially continual elevation of or application of stress to a structure without any dangerous release of applied pressure.

An important object of the invention is the provision in a structure of this character of 25 an arrangement such that the inserted stress-applying devices against which the jacks act may be held by the jacks prior to the application of strain by the jacks.

A still further object of the invention is 30 to provide a jack construction such that the holding elements of the jacks are automatically reset for withdrawal each time that stress is applied through the jack so that adequate space is provided as the jack is withdrawn to permit insertion of the device through which stress is to be applied.

A still further object of the invention is to provide in a construction of this character 40 an arrangement such that inequalities in the surfaces through which the stress is being applied may be compensated for and a uniform pressure applied to such articles.

These and other objects we attain by the construction shown in the accompanying 45 drawings wherein, for the purpose of illustration, we have shown a preferred embodiment of our invention, and wherein:

Fig. 1 is a diagrammatic showing of jack mechanism constructed in accordance with 50 our invention;

Fig. 2 is a sectional view through a preferred form of the jack element;

Fig. 3 is a similar sectional view through a modified form of jack element; and

Fig. 4 is an enlarged detail sectional view 55 through the head portion of one of the jack elements.

Referring now to the drawings, and more particularly to Fig. 1 thereof, wherein we have diagrammatically illustrated a fragment of a tunnel wall laid up in accordance with our invention set forth in the prior application hereinbefore mentioned, the numerals 10 and 11 indicate blocks of the penultimate and ultimate courses in the tunnel wall construction; 12 and 12-a indicate hydraulic jack cylinders, said cylinders being alternated and each including a piston 13 having a ram 14 attached thereto and provided with an extensible head 15. Each ram 70 has associated therewith a latch 16 by means of which the extensible head 15 may be held in withdrawn position, means being provided, as hereinafter more fully set forth, to normally maintain the head in extended position and to extend the head whenever the latch 16 is released.

The cylinders 12 are each in communication with a manifold 17 at one end thereof and at the opposite end are in communication 80 with a manifold 18, the ends thereof in communication with the manifold 17 affording the full surface of the pistons 13 while the ends thereof in communication with the manifold 18 present the surface of the piston 85 as reduced by the ram area. Similarly, the cylinders 12-a are in communication with manifolds 17-a at one end and at their opposite ends with the manifold 18. The manifold 17 is in communication with the discharge from the pumping cylinder 19 of a fluid-pressure-operated pump while the manifold 17-a is in communication with the discharge 90 of the pumping cylinder 19-a of a second pump. The intake line 20 of pumping cylinders 19, 19-a is in communication through by-pass 21 with the discharge lines of these pumps, each by-pass having a cut-off valve 22 therein. The power 95 100

cylinders 24 of the pumps are in communication with a suitable source of pressure, and preferably, with a source of dual pressure. In the present instance the pressure source 23 is shown as directly communicating with the power ends 24 of the pumps through valves 25, and is indirectly communicating with power ends of the pumps through a reducing valve 26 and the valves 25. 5 It will be obvious that by manipulation of valves 25, the pressure applied to the power ends of the pumps may be either a high or low pressure as desired and that high pressure may be applied to the pump cylinders 12 while a lower pressure is applied to the cylinders 12-a, or no pressure applied to the cylinders 12-a, or either of these arrangements may be reversed for the series 12, 12-a. The manifold 18 is in communication with a source of fluid under continual pressure, such pressure at present shown as provided through a pump 26, the storage tank for the fluid having a relief valve 27 regulating the maximum pressure which may be applied. 10 In the illustration of Fig. 1, the rams of the series 12 are shown as being advanced by high pressure fluid produced by the application of high pressure from the source 23 to the power end 24 of the associated pump, while the rams of the series 12-a are shown in positions which they may occupy at the beginning of application of low pressure fluid to the series by communication of the power end of the associated pump with the source 23 through reducing valve 26. It will be noted that one of the rams of the series 12-a is shown as advanced so that its latch 16 has engaged the extensible head 15 while the remaining rams are shown as still retracted and with their heads in engagement with the blocks 11 to hold these blocks in position until the applied fluid pressure brings the ram into its extended position and into operative engagement with the head. It will be obvious that the continued application of pressure to the rams of the series 12-a will cause all of the rams to occupy the position in which the ram of the left hand cylinder of the series is illustrated. Assuming at the same time that the application of high pressure to the rams of series 12 has advanced the blocks 10, it will be obvious that the blocks 11 will be kept in engagement with these blocks 10 throughout the movement thereof so that the blocks which form strain-applying devices in addition to forming a portion of a wall may not be displaced and more correctly positioned when the application of high pressure to the series 12-a is begun. Assuming that the advance of the rams of the series 12 has been completed, it will be obvious that by discontinuing the supply of pressure to the power end of the associated pump and opening valve 22 of

by-pass 21 of this pump, the fluid in the cylinders 12 will be expelled by the retraction of the rams through the pressure applied from manifold 18. As the rams retract, the heads operated by the latches and retracted therewith so that a space is afforded permitting of the insertion of a further row of blocks. As each block is placed in position, the latch 16 may be released and the ram head 15 extends engaging the block and holding it in its position until the application of pressure to the series is begun. 70 75

In Fig. 2 we have illustrated a preferred form of jack cylinder for use in apparatus of this character, it being understood that the following description applies equally to the cylinders 12, 12-a, which are identical in physical structure. Each cylinder 12 has one end thereof in the form of a threaded plug 28, this plug affording a nipple 29 adapted to engage in the manifold structure 30 comprising a combination of the manifolds 17, 17-a, the head or plug 28 having a port 31 communicating with the proper manifold channel 17 or 17-a. Operating 90 in the cylinder is the piston 13 which is suitably packed and which is provided with a hollow ram stem 32 projecting through the opposite end of the cylinder. This end of the cylinder is preferably reduced in diameter as at 33 to guide the ram stem 32 and is provided with a suitable packing gland 34. The ram head 15 has a stem 35 extending into the hollow ram stem and provided with piston packing 36 at its inner end. The manifold 18 communicates with the cylinder 12 adjacent the point of reduction of diameter thereof and the inner end of the hollow ram stem 32 is provided with a port opening 37 so that fluid under pressure from the manifold 18 may enter the hollow ram stem and exert pressure through the piston packing 36 upon the ram head to extend the same. The ram head is formed in two sections, of which the inner, 38, is preferably integrally attached to the stem 35 and has at one side thereof an extension 39 forming a latch catch co-acting with the spring-pressed latch element 40 carried by the outer end of the hollow ram stem 32. This section has in its outer face a concave socket 41 for receiving the inner end of a convexly curved projection 42 formed on the outer section 43 of the head which is loosely secured to the section 38 through a suitable securing element 49. Adjacent faces of the sections about the socket 41 and the projection 42 are rabbeted to receive cushion material 45 which will yield to permit oscillation of the outer head section 43, but will, upon release of pressure to the head, restore the outer head section to its normal position with relation to the ram. 100 105 110 115 120 125

The construction shown in Fig. 3 differs from the construction just described only in the fact that the means for extending the 130

- ram head is modified, a spring 46 being employed for this purpose and extending between the inner end of the ram head stem 35—a and a seat 47 secured interiorly of the hollow stem 32—a of the ram. This seat preferably, likewise, forms the anchoring means for a dash pot cylinder 48 the piston 49 of which is connected to the ram head stem 35—a and serves to cushion the 10 operation of spring 46 and prevent the ram head from too sudden extension upon release of catch 16. Catch 16 in each of these constructions is normally urged to its latching position by a suitable spring 50 and provided with a bevelled nose 51 adapted to ride over the projection 39 as the ram stem extends and, thus, automatically assume its latching position when the ram stem is fully extended.
- 20 It will be obvious in each of these constructions the release of the latch 16 will result in immediate extension of the ram head 15, this extension resulting in the construction of Fig. 2 from fluid pressure applied through the 25 manifold 18 and the construction of Fig. 3 from the action of spring 46. It will also be obvious that in each instance when the ram is extended the latch 16 will automatically re-engage the head so that when the ram is 30 again retracted the head will be disposed in its normal position with relation to the ram and will not interfere with the application of elements through which strain is to be applied.
- 35 Since the construction illustrated is, obviously, capable of a certain range of change and modification without in any manner departing from the spirit of our invention, we do not wish to be understood as limiting ourselves thereto except as hereinafter claimed.
- We claim.
1. A jack for tunneling machines comprising a cylinder, a piston therein, a ram connected with the piston, an extensible head 45 carried by the ram, a spring for extending said head, and means for retaining the head in retracted position.
2. A jack for tunneling machines comprising a cylinder, a piston therein, a ram connected with the piston, an extensible head carried by the ram, a spring for extending said head, means for retaining the head in retracted position and a dash-pot resisting movement of the head to its extended position when released.
3. A jack for tunneling machines comprising a cylinder, a piston therein, a ram connected with the piston, an extensible head carried by the ram, a spring for extending 50 said head, and means for retaining the head in retracted position, the ram being hollow, the head having a stem slidably engaged in the ram.
4. A jack for tunneling machines comprising a cylinder, a piston therein, a ram con-
- nected with the piston, an extensible head carried by the ram, a spring for extending 55 said head, and means for retaining the head in retracted position, the ram being hollow, the head having a stem slidably engaged in 70 the ram, the spring being housed within the hollow ram.
5. A jack for tunneling machines comprising a cylinder, a piston therein, a ram connected with the piston, an extensible head carried by the ram, a spring for extending said head, and means for retaining the head in retracted position, the ram being hollow, the head having a stem slidably engaged in the ram, said head being oscillatable upon said 75 stem.
6. A ram head for the rams of jacks of tunneling machines comprising two plates connected for limited oscillatory movement and resilient material interposed between the peripheral portions of said plates.
7. A jack for tunneling machines, comprising a ram, means for shifting said ram, an extensible head carried by the ram, a spring for extending said head and means for retaining the head in retracted position.
8. A jack for tunneling machines, comprising a ram, means for shifting said ram, an extensible head carried by the ram, a spring for extending said head, means for retaining the head in retracted position and a dash-pot resisting movement of the head to its extended position when released.
9. A jack for tunneling machines comprising a ram having an extensible head including a stem slidably engaged in a bore formed in the ram, means for extending the head and means for maintaining the head in retracted position.
10. A jack for tunneling machines comprising a cylinder, a piston therein, a ram connected to the piston, said ram comprising a cylinder, a head carried by the ram and having a stem piston packed to the walls of the ram, said ram having a port formed therein 100 adjacent the piston.
11. A jack for tunneling machines comprising a cylinder, a piston therein, a ram connected to the piston, said ram comprising a cylinder, a head carried by the ram and having a stem piston packed to the walls of the ram, said ram having a port formed therein 110 adjacent the piston, and a latch for retaining said head in retracted position.
12. A jack comprising a cylinder, a piston 115 therein, a ram connected with the piston, an extensible head carried by the ram, means constantly urging the head to extended position, and a latch for maintaining the head in retracted position.
13. A jack comprising a cylinder, a piston 120 therein, a ram connected with the piston, an extensible head carried by the ram, means constantly urging the head to extended position, and a latch for maintaining the head 125
14. A jack comprising a cylinder, a piston 130 therein, a ram connected with the piston, an extensible head carried by the ram, means constantly urging the head to extended position, and a latch for maintaining the head

in retracted position, said latch automatically reengaging with the head upon pressure contact of the head with an article to which strain is being applied by the jack.

14. In jack apparatus, a plurality of hydraulic jacks each embodying a ram having an extensible head, said jacks being arranged in a plurality of series, means constantly urging the extensible heads of all of the jacks to extended position, releasable latching means associated with each jack for preventing extension of the head, the latching means automatically reengaging upon pressure engagement of the ram head with an article to which strain is to be applied, and means for selectively applying pressure to a selected series of jacks.

15. A device as claimed in claim 14 where-in the means tending to extend the heads of the jacks constantly yieldably urges the rams of the jacks to retracted position.
